HERBERT B. TAYLOR, OF ROCHESTER, NEW YORK, ASSIGNOR TO GENERAL RAILWAY SIGNAL COMPANY, OF ROCHESTER, NEW YORK

SWITCH MACHINE

Application filed June 8, 1929. Serial No. 369,395.

This invention relates to electrically controlled switch machines for railroads, and more particularly to mechanisms and circuits associated therewith for controlling a switch machine having two field windings.

Among the objects of this invention are to provide contacts and circuit arrangements for remotely controlling the normal and reverse operations of a switch machine over 10 two control wires in conjunction with a common return wire; to provide means whereby the momentum of the motor armature may be dynamically braked at the end of its operations through local circuits; to provide 15 means whereby operation in the opposite direction can not occur while the armature is being dynamically braked; to provide means whereby the dynamic braking circuit is maintained only while such braking occurs; 20 and to provide an arrangement of circuits so that a cross during operation will cause the motor to stop.

This invention is particularly adaptable to control circuits for switch machines, 25 where the positions assumed by the track switch are repeated in the interlocking tower by means of constant current source indication circuits as compared with dynamic indication circuits. Also, this invention provides 30 means whereby the last few revolutions of the motor armature generates a current, which is shunted through a snubbing or dynamic braking circuit local to the switch machine. Such an arrangement permits the 35 control of a switch machine from long distances, which would be too great to permit the dynamic braking of the switch machine to be carried through the contacts of its control lever, as is the usual practice, due to the high 40 resistance of the intervening control wires.

Other objects, purposes and characteristic features of the invention will be in part obvious from the accompanying drawing and in part pointed out as the description of the 45 invention progresses.

The single figure of drawing shows diagrammatically one specific embodiment of the present invention as applied to a switch machine having two field windings associated 50 with its armature.

Referring now to the single figure of the drawing, the switch machine SM is shown associated with a track switch TS at the east end of a passing siding PS. This track switch TS is controlled to its reverse or normal position through a throw bar governed by the motion of the armature A of the switch machine SM in any suitable manner, such for instance as set forth in the patent to W. K. Howe, No. 1,288,595, dated December 24, 1918. 55 Associated with the throw bar of the switch machine SM, is the cam wheel CW which has a projection CW¹. This cam wheel CW rotates in a direction denoted by the arrow R when the switch TS moves to a reverse position, until the projection CW¹ assumes its dotted position CW². In other words, the motion of the cam wheel CW begins with the movement of the track switch TS and assumes its extreme positions at the same time 60 that the track switch TS assumes its extreme position. The armature A has associated with it the field windings F¹ and F², which are controlled through circuits passing through the contact members 1 and 2 mounted upon the mechanically actuated and electrically held armatures 3 and 4 of the electric stick relays SR¹ and SR² respectively. The armatures 3 and 4 normally resting on 65 stop pins 3^a and 4^a, respectively, have associated therewith one-way dogs 5 and 6, which are engaged at certain times by the levers 7 and 8. These one-way dogs 5 and 6 are pivoted upon the armatures 3 and 4 respectively and are biased by gravity or other suitable 70 means so that the elongated ends assume a downward position to the extent permitted by the stop pins 5^a and 6^a. The manner in which these one-way dogs are prevented from moving in one direction by the stop pins 5^a 75 and 6^a, respectively, is obvious from the drawings. The levers 7 and 8 are biased to extreme positions by some suitable means such as coil springs, which extreme positions are determined by their respective stationary contacts, and are moved from their extreme, biased positions at certain times, namely when 80 they are engaged by the projection CW¹.

The switch machine SM is controlled over a normal and a reverse control wire in con-

junction with a common wire, receiving energy from any suitable source such as the battery BT, the switch machine being controlled through the lever L. This lever L for convenience has been shown as a simple hand throw switch, but may be any suitable circuit controller used in general practice for such purposes. Tower equipment and other controls associated with the governing of a 10 remotely controlled switch machine may be according to any standard method, such for instance as the control circuits set forth in an application by W. K. Howe, Ser. No. 337,000, filed February 2, 1929.

15 It is believed that the invention will be better understood from the stand point of operation.

Operation

20 Let us assume that the operator desires to move the track switch TS to a reverse position, which may be accomplished by moving the lever L to its dotted line position. With the lever L in its dotted line position, positive potential is applied to the field winding F² and the armature A over a circuit traced as follows:—from the positive terminal of battery BT, through lever L, the reverse control wire, lever 8, wire 9, contact member 1, wires 10 and 11, field winding F², armature 25 A, through the common wire to the negative terminal of battery BT. The cam wheel CW now begins to rotate in a direction denoted by the arrow R, as the switch machine begins the operation of the track switch TS to a 30 reverse position.

As soon as the projection CW¹ moves sufficiently in a counter clockwise direction, the lever 7 moves past the one-way dog 5 without disturbing the armature 3 of a relay SR¹, 40 and closes the normal control circuit with which it is associated. When the projection CW¹ is moved to its dotted line position CW² at the same time that the track switch TS assumes its reverse position, the lever 8 is moved 45 to its dotted line position, thus moving the armature 4 to its upper position so that a potential which is generated by the armature A and the field winding F¹ flows through a circuit to hold the armature 4 in an energized 50 position until the armature A comes to rest. This snubbing circuit is traced as follows:— from the positive terminal of the armature A through the field winding F¹, wires 12 and 13, winding of relay SR², wire 14, armature 4, 55 through the common wire to the opposite terminal of the armature A.

At the same time that the lever 8 moves to its dotted line position the energizing circuit heretofore traced for the switch machine is broken at the contact associated with lever 60 8, and is not again completed, until the switch machine has been controlled to operate in a direction indicated by the arrow N for operating the track switch TS to its normal 65 position.

As soon as the armature A comes to rest, the induced current, which flows through the snubbing circuit heretofore traced dies out so that the relay SR² becomes deenergized and allows the armature 4 to drop away to its deenergized position, allowing the switch machine to be operated for controlling the track switch to its normal position at the option of the operator.

Let us now assume that the switch L is returned to its full line position, at which time positive potential will be applied to operate the switch machine SM through a circuit traced as follows:—from the positive terminal of battery BT, through the normal control wire, lever 7 in its dotted line position, wire 15, contact member 2, wires 16 and 12, field winding F¹, armature A, through the common wire to the negative terminal of battery BT. The armature A now rotates in a direction to control the cam wheel CW in a direction denoted by the arrow N, and to control the track switch TS to a normal position. As soon as the projection CW¹ moves away from engagement with the lever 8, said lever 8 assumes its present full line position, and at the completion of the operation of the track switch TS to a normal position the projection CW¹ engages the lever 7 and moves it to its present full line position at the same time forcing the armature 3 to an upper position which it maintains, until the induced snubbing current dies out. This snubbing circuit for the switch machine when operating to the normal position is traced as follows:—from the positive terminal of the armature A through the field winding F², wires 11 and 17, winding of relay SR¹, wire 18, armature 3, through the common wire to the opposite terminal of the armature A.

When the armature A comes to rest, the induced current ceases to flow through the winding of relay SR¹ and allows the armature 3 to assume its present full line position. Thus, the operation of the switch machine control, as included within the present invention, has been described to an extent including its operation from its normal position to its reverse position and its operation from its reverse position back to its normal position.

It is noted that a cross between the control wires results in current flowing through both field windings, which then neutralize each other to the extent of stopping the motor. Such a result is highly desirable and must be provided for in all arrangements of dynamic braking through local circuits.

Having set forth one specific illustration of the present invention, it is desired to be understood that the present invention may be adapted to be used with any particular switch machine having two field windings associated with its armature.

It is to be understood, that the cam wheel CW may be controlled in any suitable manner,

one modification of which might be an adaptation to be controlled by a point detector as set forth by C. S. Bushnell in Patent No. 1,517,236, dated November 25, 1924, inasmuch as a second projection such as CW¹ could be placed upon the circumference of cam wheel CW in such a position that the limited rotation of the cam wheel CW effected by the point detector would still effect the control of the levers 7 and 8. Also, the cam wheel CW¹ could be operated to an intermediate position at the beginning of the stroke and to an extreme position at the end of a stroke, in a similar manner to the above referred to point detector in Patent No. 1,517,236, without in any manner affecting the operation of the present invention.

Although the construction of one embodiment of the invention has been specifically described and the operation and principles thereof explained, nevertheless it is desired to have it understood, that the form selected is merely illustrative, and does not limit the possible physical embodiments of the idea or means underlying the present invention, as many modifications and adaptations can be made without departing from the spirit of the invention as set forth by the appended claims.

30. What I claim is:

1. Apparatus for operating a distant track switch comprising, a switch machine having a reversible motor, a source of electrical current and means for automatically snubbing the rotation of said motor upon the completion of either normal or reverse operations including, contacts operated by said switch machine for disconnecting said motor from possible connection with said source of current upon completion of operation of said track switch, contacts operated by said switch machine for shunting said motor upon completion of either normal or reverse operations, which contacts are held closed only until said motor ceases rotation, and contacts which complete the control circuit for operation of said switch machine in the opposite direction when said motor ceases to rotate, whereby the rotation of said armature is snubbed at the end of each operation through means local to said switch machine.

2. Apparatus for operating a distant track switch comprising, a reversible switch machine having an armature and a field winding being controlled from a distant point through either a normal or a reverse control wire in conjunction with a common wire, manually controlled source of current, and means for automatically snubbing the rotation of said armature upon completion of either normal or reverse operations including, contacts mechanically operated by said switch machine for disconnecting said field windings from said manually controlled source of current upon completion of operation of said track switch, contacts operated by said switch machine for shunting said armature in series with the particular one of said fields which is deenergized during a particular operation, which contacts are held closed only until said armature ceases rotation, and contacts which complete the control circuit for operation of said switch machine in the opposite direction

track switch, contacts mechanically operated by said switch machine for shunting said armature and said field windings, which contacts are held closed only until said armature ceases rotation and contacts which complete the control circuit for operation of said switch machine in the opposite direction when said armature ceases to rotate, whereby the rotation of said armature is snubbed at the end of each operation through means local to said switch machine.

3. Apparatus for operating a distant track switch comprising, a switch machine having a reversible motor including an armature and field windings which are connected in externally controlled combinations in series with a manually controlled source of current to produce rotation of said armature in either of two directions over either a normal or a reverse control wire in conjunction with a common wire, and means for automatically snubbing the rotation of said armature at the completion of either normal or reverse operations of said track switch including, contacts mechanically operated by said switch machine for disconnecting a particular control wire from said motor at the completion of operation of said track switch to its corresponding extreme positions, contacts mechanically operated by said switch machine for shunting said motor which contacts are electrically held closed by the dynamic current of said motor until said armature ceases to rotate, and contacts electrically held open which are released to complete the control circuit for the operation of said switch machine in the opposite direction when said armature ceases to rotate, whereby the rotation of said armature is snubbed at the end of each operation through means local to said switch machine.

4. Apparatus for operating a distant track switch comprising, a switch machine having a reversible motor including two field windings one of which is connected in series with the armature and a source of current to produce rotation in one direction, and the other of which is connected in series with the armature and a source of current to produce rotation in the opposite direction, means for automatically snubbing the rotation of said armature upon the completion either normal or reverse operations including, contacts operated by said switch machine for disconnecting both field windings from possible connection with said source of current upon completion of operation of said track switch, contacts operated by said switch machine for shunting said armature in series with the particular one of said fields which is deenergized during a particular operation, which contacts are held closed only until said armature ceases rotation, and contacts which complete the control circuit for operation of said switch machine in the opposite direction

when said armature ceases to rotate whereby the rotation of said armature is snubbed at the end of each operation through means local to said switch machine.

5. Apparatus for operating a distant track switch comprising, a switch machine having a reversible motor including two field windings one of which is connected in series with the armature and a manually controlled source of current to produce rotation in one direction, and the other of which is connected in series with the armature and a manually controlled source of current to produce rotation in the opposite direction, means for automatically snubbing the rotation of said armature upon completion of either normal or reverse operation including, contacts operated by said switch machine for disconnecting both field windings from said manually controlled source of current upon completion of operation of said track switch, contacts operated by said switch machine for shunting said armature in series with the particular field which was deenergized during a particular operation, which contacts are held closed only until said armature ceases rotation, and contacts which complete the control circuit for operation of said switch machine in the opposite direction when said armature ceases to rotate, whereby the rotation of said armature is snubbed at the end of each operation through means local to said switch machine.

6. Apparatus for operating a distant track switch comprising, a switch machine having a reversible motor including two field windings one of which is connected in series with the armature and a source of current to produce rotation in one direction, and the other of which is connected in series with the armature and a source of current to produce rotation in the opposite direction, means for dynamically braking the rotation of said armature upon the completion of either normal or reverse operations including, a plurality of contacts mechanically controlled by said switch machine, and a plurality of contacts mechanically actuated by said contacts mechanically controlled, which mechanically actuated contacts are electrically held, whereby local circuits, for dynamically braking said armature of said motor, are completed only at the completion of operation of said track switch to either extreme position.

7. Apparatus for operating a distant track switch; comprising a switch machine having a reversible motor including two field windings one or the other of which is connected in series with the armature of such motor depending on whether the normal or the reverse wire is connected to a source of current; contacts operated by said switch machine included in said normal and said reverse wire of which the contacts in the normal wire are open in the normal position of said switch machine, are closed in any intermediate position

of said switch machine and open in the reverse position of said switch machine until the rotation of said armature has ceased, and of which the contacts in the reverse wire are open in the reverse position of said switch machine closed in any intermediate position of said switch position and open in the normal position of said switch machine until the rotation of said armature has ceased; contacts operated by said switch machine for shunting said armature in series with the particular one of said field windings which is deenergized during a particular operation, a common wire connecting said armature to one side of a source of current, and a control lever for connecting the other side of said source to either the normal or reverse wire, whereby said switch machine motor may be dynamically braked by a circuit wholly local to said switch machine, and whereby said switch machine may not be controlled for operation in the opposite direction while said motor is being dynamically braked.

8. Apparatus for operating a distant track switch comprising, a switch machine having a reversible motor including two field windings one of which is connected in series with the armature and a manually controlled source of current to produce rotation of said armature in one direction, and the other of which is connected in series with the armature and a manually controlled source of current to produce rotation of said armature in the opposite direction, means for automatically snubbing the rotation of said armature at the completion of either normal or reverse operations of said track switch including, contacts mechanically operated by said switch machine for disconnecting both field windings from said manually controlled source of current at the completion of operation of said track switch to either of its extreme positions, contacts mechanically operated by said switch machine for shunting said armature in series with the particular field winding which is deenergized during a particular operation, which contacts are electrically held closed by the dynamic currents of said motor until said armature ceases to rotate, and contacts electrically held open which are released to complete the control circuit for the operation of said switch machine in the opposite direction when said armature ceases to rotate, whereby the rotation of said armature is snubbed at the end of each operation through means local to said switch machine.

9. In combination with a railway track switch, the combination with a reversible electric motor operated switch machine, a distant control means for controlling said switch machine to operate said track switch, and a contact means controlled by said switch machine for disconnecting said control means and for dynamically braking said switch machine.

chine through circuits wholly local to said switch machine, whereby said switch machine can not be operated in an opposite direction while said switch machine is being dynamically braked.

5 10 15 20 25 30 35 40 45 50 55 60 65

10. In combination with a railway track switch, the combination with a reversible electric motor operated switch machine, a distant control means for controlling said switch machine to operate said track switch to either of two extreme positions, and contact means mechanically operated at the end of each operating stroke of said switch machine for closing a dynamic braking circuit including means for maintaining said braking circuit closed by the dynamic indication current flowing therein.

In testimony whereof I affix my signature.
HERBERT B. TAYLOR.
